UNITED STATES PATENT OFFICE.

WILLIAM A. DOBLE AND OYSTEIN JACOBSEN, OF SAN FRANCISCO, CALIFORNIA, ASSIGNEES TO PELTON WATER WHEEL COMPANY, OF SAN FRANCISCO, CALIFORNIA, A CORPORATION OF CALIFORNIA.

DEEP-WELL PUMP.

1,285,644.

Specification of Letters Patent. Patented Nov. 26, 1918.

Application filed October 25, 1915. Serial No. 57,716.

To all whom it may concern:

Be it known that we, WILLIAM A. DOBLE, a citizen of the United States, and OYSTEIN JACOBSEN, a subject of the King of Norway, 5 residents of the city and county of San Francisco, State of California, have invented certain new and useful Improvements in Deep-Well Pumps, of which the following is a specification.

10 The invention relates to deep well pumps and particularly to the automatic lubrication of bearings and the automatic hydraulic balance of the runners in such pumps.

An object of the invention is to provide 15 for successful automatic water lubrication of the pump and pump shaft.

Another object of the invention is to provide means whereby the bearings are 20 flushed with water continuously during the operation of the pump, to prevent the accumulation of any particles of grit in the bearings.

A further object of the invention is to 25 provide automatic hydraulic balance means for the runner.

The invention possesses other advantageous features, some of which with the foregoing, will be set forth at length in the following description where we shall outline in full that form of the invention which we have selected for illustration in the drawings accompanying and forming part of the present specification. In the drawings we have shown several specific

30 forms of our generic invention, but it is to be understood that we do not limit ourselves to such forms because the invention may be embodied in a multiplicity of forms, each being a species of the said invention.

35 It is also to be understood that by the claims succeeding the description of our invention, we desire to cover the invention in whatever form it may be embodied.

Considerable difficulty has been experienced in lubricating deep well centrifugal pumps on account of the inaccessibility of the apparatus due to its position in deep bore holes. This difficulty has not only been overcome by our invention, but we have 40 provided a lubricating system which is automatic in operation and which does not act to pollute the water being pumped. This is accomplished by employing water as the lubricating agent and by causing the

water to flow in such quantity that the 55 bearings are continually flushed. We have also provided means for the automatic water lubrication of the drive shaft bearings, so that no lubricating oil or grease need be used on those parts of the 60 pumping apparatus which are arranged within the bore hole. The practice of using oil or grease as a lubricant is highly objectionable when the water pumped is used by breweries, creameries or for 65 portable purposes, since no matter how carefully and accurately the pumps may be constructed, the oil or grease will work its way out of the pump into the water, and even if the oil or grease is present in the 70 water in comparatively small quantity, it is still highly objectionable. Water, and particularly the water taken directly from the well, often contains small particles of hard or gritty substances, which, when the 75 water is used as a lubricant, will come in contact with the bearings. We have found, however, that if this grit is not allowed to accumulate in the bearings, that its presence is not deleterious and that it 80 does not act to cut the bearings. In order to prevent it from accumulating we supply sufficient water to the bearing so that it continually flushes therethrough, carrying the grit with it and preventing it from 85 accumulating in pockets.

Referring to the accompanying drawings:

Figure 1 is a vertical section of a deep well pump, casing and drive shaft constructed in accordance with our invention, the pump being water lubricated.

Fig. 2 is a vertical section of a portion of the well casing and pump casing, showing means for the automatic water lubrication of the drive shaft bearing.

Fig. 3 is a vertical section of the pump, showing one form of water lubricated construction.

Fig. 4 is a similar view showing a modified form of water lubricated construction.

Fig. 5 is a similar view, showing means for counterbalancing the weight of the runner.

Fig. 6 is a similar view showing a modified form of counterbalancing means.

Fig. 7 is a similar view showing means for producing dynamic balance of the runner,

Fig. 8 is a top view of the runner shown in Fig. 7.

The pump is arranged within the well casing 2, at a suitable depth so that water 5 may readily flow or be drawn into it by the rotation of the runner. The pump shell 3 is supported by the pump tube 4 which is supported at the upper end of the well and depends into the well and through this tube 10 4 the water is pumped to the surface. The drive shaft 5 is suitably supported at the upper end of the well and extends downward within the pump tube. Arranged within the pump tube and spaced apart 15 therefrom, is an inner tube 6, which provides a smooth annular passage between it and the pump tube for the water being pumped. It is important that the passage through which the water is pumped be smooth, so that eddy currents and other disturbances 20 may be avoided, since the presence of these disturbances reduces the efficiency of the pump. The pump casing 7 is provided with substantially vertical vanes 8 and the pump 25 shell 3 is provided with vanes or ribs 9 which are of decreasing curvature upward, so that the water from the pump enters the annular passage in a substantially vertical direction and substantially free of 30 disturbances.

A bearing 12 of the lower end of the pump shaft is arranged within the pump shell. The bearing 12 is preferably formed as a separate element and is pressed into the 35 hub 13 of the pump shell or otherwise rigidly secured thereto. The pump shell is formed with an inner wall 14 which substantially parallels the outer wall, forming therebetween an annular passage for the water being pumped and the inner wall 14 and the hub supporting wall 15, form within the pump shell, a chamber 16 through which the drive shaft extends. The inner wall 14 is provided with a depending flange 17 extending 40 below the hub wall 15 and the flange 20 on the upper wall 18 of the conoidal runner 19 extends upward alongside of the flange 17 forming a running joint therewith. Secured to the bearing 12 or the inner wall 14 45 or other stationary part of the pump shell is a wall 21 which lies adjacent the other side of the wall 18 and forms a running joint therewith. The hub wall 15 is provided with apertures 22 which establish communication 50 between the pocket formed between the walls 17 and 21 and the chamber 16.

When the pump is operating, a pressure is produced at the periphery of the runner and this pressure forces water up through 60 the joint between the flange 17 and the upper wall 18 of the runner, through the apertures 22 and into the chamber 16. The water thus circulated flows downward around the drive shaft through the grooves 23 in the bearing 12 maintaining perfect water lubri-

cation of the bearing and flushing out any grit particles carried by the water. After passing through the bearing the water discharges into the chamber 24 formed above the upper wall of the runner, whence, in the 70 construction shown in Figs. 3 and 4, it is discharged into the runner by the vanes 25.

In Fig. 4 we have shown a shaft bearing 26 arranged below the hub 27 of the runner and have also provided means for the hydraulic lubrication and flushing of this bearing. A pipe 28 taps the chamber 16 at the level of the top of bearing 12 and conveys water into the bearing 26 at about the center, the bearing being provided with grooves 29 80 for distributing the water over the entire length of the bearing. The water which passes downwardly in the bearing discharges through the passage 31 and that which passes upwardly in the bearing discharges through the running joint between the runner hub and the exterior of the bearing.

In the construction shown in Fig. 1 the hub 13 is supported from the wall 14 by ribs 90 32, thereby eliminating the use of the hub wall 15, and the bearing flange 21 is supported from the bearing by suitable ribs. The lubricating water in this instance passes up through the running joint between the 95 flange 17 and the flange 20, down between the flange 20 and flange 21 and thence up into chamber 16. After passing through the bearing 12 the water discharges into a chamber 33 formed within the bearing structure, whence it passes through the apertures 34 into the chamber 24 formed between the bearing structure and the upper wall of the runner. From here some of the water passes directly back into the chamber 16 through the aperture between the bearing structure and the flange 21 and some discharges through a variable aperture between the upper wall of the runner and the bearing structure and is driven into the runner by 101 the vanes 25. The purpose of the variable aperture and the chamber 24 will be set forth hereinafter.

Means are also provided for lubricating the bearings of the drive shaft 5. In Fig. 1 111 we have shown an oil lubricated bearing and in Fig. 2 a water lubricated bearing, which is lubricated by the water in the well. The bearing 36 is arranged in a spider 37 which is clamped between the adjacent ends of the 12 pump tube sections 4 by bolts 38 engaging flanges 39 screwed to the ends of the tube sections. The outside diameter of the bearing is slightly less than the inside diameter of the inner tube 6, so that the ends of the 12 tube sections may be slipped onto the projecting ends of the bearing. This arrangement constitutes in effect an expansion joint and prevents strains which might be set up in the inner tubing from throwing 13

the pump out of alignment. Since the function of the inner tube is to make a smooth passageway for the water being pumped and since the entrance of water into the interior of the inner tube is advantageous

5 rather than deleterious, the joint between the inner tube and the bearing is not made water tight, but is a sliding fit for the reasons heretofore set forth. Heretofore the 10 inner tube sections have been rigidly connected together for their entire length and strains set up therein have thrown the pump out of alignment.

15 The bearing bushing 41 is provided with one or more grooves 42 on its bearing surface through which the lubricating liquids flow. Through each bearing extends a passage 43 which is provided at its upper end with a short stand-pipe 44 through which 20 any excess of lubricating liquid flows to the bearing below. When oil is used as a lubricant it may be introduced into the upper end of the inner tube. We prefer, however, to 25 employ water as the bearing lubricant since oil causes a contamination of the water being pumped and because a tube structure which prevents the entrance of water into the inner tube throws undue strains on the pump. Extending through the spider 37 is 30 a passage 45, opening at one end into the well and at the other end into the inner tube, the latter end being provided with a stand-pipe 46. Water from the well passes through 35 the passage 45 into the inner tube above the bearing and passes through the bearing, keeping it constantly flushed. After passing through the bearing, the water descends to the bearing next below, and finally discharges into the well or the pump runner.

40 Means are also provided for counterbalancing the weight of the runner during the operation of the pump. To relieve the counterbalancing means of the weight of the drive shaft and still allow the runner to 45 move vertically through a limited distance to vary the hydraulic counterbalancing pressure, the drive shaft is divided at its lower end into two parts. The lower part 51 to which the runner is secured is connected to the upper part of the shaft by a coupling 52 in which the lower portion is splined.

When the pump is not operating, the runner is supported on the step 53 arranged in the suction inlet (Fig. 1) or upon some other 55 portion of the pump shell. When the pump is operating the pressures produced in counterbalancing chambers raise the runner and hold it in suspension. The chamber 24 which occurs above the upper wall 18 of the runner communicates with the interior of the runner at the inner or suction end of the runner vanes, so that a decrease of pressure is produced in the chamber which exerts a lift on the runner. The chamber 54 which 60 occurs between the lower wall of the runner

and the pump shell receives water under pressure from the runner discharge, thus producing a pressure in this chamber which exerts a lift on the runner. For a substantially constant speed of the runner the pressure in chamber 54 is substantially constant, and the pressure in chamber 24 is variable depending upon the vertical position of the runner. When the combined pressures in these chambers are not sufficient to balance 70 the runner, for various reasons, means are provided for producing a third upward pressure. This means is shown in Figs. 1 and 6 and consists in an extension 55 outwardly of the upper wall of the runner beyond the 75 vanes, so that an upward pressure is exerted on this area.

In the constructions shown in Figs. 5 and 6, the bearing structure is provided with a hub 56 and the upper wall of the runner is provided with a passage 57 surrounding the shaft and lying directly below the hub 56, through which water passes from the chamber 24 into the chamber 58 formed between the upper wall of the runner and the runner 90 hub 27. Vanes 59 arranged in chamber 58 discharge the water into the runner and produce a reduction of pressure in chamber 24. The water from chamber 24 discharges through the passage between the hub 56 and 95 the upper wall 18 of the runner and as the runner moves vertically the area of this passage is varied. When the runner raises to close the passage the pressure in chamber 24 increases, forcing the runner down, 100 resulting in an opening of the passage and a lowering of the pressure in the chamber. The runner adjusts itself vertically in balance and any variations in the downward forces are counterbalanced by variations in 105 pressure in the chamber 24. In the construction shown in Fig. 7, the upper wall of the runner is provided with a renewable wearing ring 61, which is bolted to projections 62 on the runner. In order to secure a perfect 110 operation of the runner, it is necessary that the runner be in dynamic balance. In order to effect this balance, the balancing lugs or projections 62 are provided and should the runner be out of dynamic balance, 115 the amount of metal necessary to secure this balance may be removed from the proper projection or projections. These projections are spaced apart circumferentially and their edges are curved so that they form 120 vanes for discharging the water into the runner.

We claim:

1. In a deep well pump, a drive shaft, an inner tube surrounding said shaft, a bearing for said shaft arranged within said tube and means for introducing water directly from the well into the tube above said bearing for the purpose of lubricating the bearing. 125

2. In a deep well pump, a drive shaft, a pump tube surrounding the shaft, a shaft bearing supported by said pump tube, an inner tube surrounding the shaft and engaging the bearing and a conduit through the bearing for conducting water from the well into the inner tube above the bearing for the purpose of lubricating the bearing. 50
3. In a deep well pump, a drive shaft, a pump tube formed in sections surrounding the drive shaft, a spider clamped between the adjacent ends of the pump tube sections, a shaft bearing in said spider, an inner tube surrounding the shaft and engaging the outer surface of the bearing and a conduit extending through said spider and bearing and opening on one end within the inner tube and at the other end within the well for the purpose of water lubricating said bearing. 60
4. In a deep well pump, a drive shaft, a pump tube formed in sections surrounding said shaft, a spider clamped between the adjacent ends of the pump tube sections, a shaft bearing in said spider having a grooved bearing surface, an inner tube surrounding the shaft and slidably engaging the outer surface of the bearing and a conduit extending from the exterior of the pump tube to the interior of the inner tube above the bearing for the purpose of conducting well water into the inner tube for lubricating the bearing. 70
5. In a deep well pump, a drive shaft, a pump tube, a pump casing attached to the pump tube, an inner tube surrounding the drive shaft and engaging the pump casing and a slidable joint in said inner tube. 80
6. In a deep well pump, a drive shaft, a pump casing, an inner tube surrounding the shaft and engaging the pump casing and a slidable joint in said inner tube. 90
7. In a deep well pump, a drive shaft, a pump casing, a bearing for said drive shaft and an inner tube surrounding the shaft and slidably engaging said bearing and pump casing. 85
8. In a deep well pump, a drive shaft, a pump casing into which said shaft extends, a bearing for said shaft and an inner tube 55 surrounding the shaft and engaging the pump casing and forming a sliding joint with the bearing. 95
9. In a deep well pump, a pump shell having a chamber therein, a drive shaft extending through said chamber, and a bearing for said shaft having its upper end disposed in said chamber, said chamber being in communication with the pump chamber whereby water is introduced into said chamber for lubricating said bearing. 60
10. In a deep well pump, a pump shell having a chamber therein, a runner in said shell, a drive shaft attached to said runner, and a bearing for said shaft extending into said chamber, said shell being provided with passages whereby water under pressure from the runner is forced into said chamber for the purpose of lubricating the bearing. 65
11. In a deep well pump, a pump shell having a chamber therein, a runner in said shell having an upper wall which forms a running joint with the shell, a bearing in said shell, the upper portion of said bearing lying within said chamber, and a passage 75 to permit the water passing said running joint to enter said chamber and lubricate the bearing. 70
12. In a deep well centrifugal pump, the combination of a pump shell, a runner mounted on a shaft and revoluble within the shell, a bearing for said shaft arranged above the runner and provided with grooves extending therethrough, means for flowing water through said grooves to lubricate the bearing, a chamber into which said water is discharged, and a passage, the area of which is controlled by the vertical position of the runner, connecting said chamber with the interior of the runner. 80
13. In testimony whereof we have hereunto set our hands at San Francisco, California, this 19th day of October, 1915. 90

WILLIAM A. DOBLE.
OYSTEIN JACOBSEN.
